WILLIAM F. COBB, OF WHITESTOWN, INDIANA.

Letters Patent No. 78,060, dated May 19, 1868.

IMPROVEMENT IN TENONING-MACHINES.

The Schedule referred to in these Letters Patent and making part of the same.

TO ALL WHOM IT MAY CONCERN:

Be it known that I, WILLIAM F. COBB, of Whitestown, in the county of Boone, in the State of Indiana, have invented a new and useful Improvement in Tenoning-Machines; and I do hereby declare that the following is a full and exact description thereof, reference being had to the accompanying drawings, and to the letters of reference marked thereon.

Figure 1 represents a front elevation of my new machine.

Figure 2 represents a side elevation of the same; and

Figure 3 is a view of the adjustable chisel detached.

An iron frame, B, is fastened to the table A, upon which the lumber rests. The arms C, which are fastened to frame B, are made fast by screws to the block D, and support the operating-mechanism above the table, A. The central block, D, is perforated with four holes, through which the fixed guide-rods, a a, are inserted. The slot m, in the centre of the block D, is made for the chisel-rod, b, to work in. On the sides of the central block, D, there are two plates, 1 1, on which lips, 2 2, are formed, to serve as supports and guides for the four rack-bars, 3, which connect the chisel-bar holders or guides, 4. The racks, 3, serve to adjust the chisels, with their holders and guides, towards or from each other, which may be done by the crank, 5, with its shaft and two pinions, 6, which work on both edges of block D, and mesh into the two pairs of rack-bars, 3. The supporting guide-rods, a a, pass through the chisel-bar holders or guides, 4, so as to permit them to be adjusted by the racks, 3. The front chisel-bar, 7, is slotted, to correspond with the slot m, in central block D, and a shipping-latch, 8, is hinged to the bar 7 below the slot. Latch 8 may be thrown into connection with the chisel-rod b, as indicated in dotted lines, or it may be thrown outwardly, so as to connect with pin 9, which projects from the side of the chisel-bar guide, 4. The curved notch, near the upper end of latch 8, will, when shipped into the position indicated in dotted lines, embrace the chisel-rod, b, and thereby the chisel-bar, 7, will be forced to ascend and descend with the rear chisel-bar, through which the chisel-rod b also passes, and, by moving latch 8 outwardly, so as to connect it with the pin 9, the chisel-rod, b, will descend in the slot m, and the slot in chisel-bar, 7, leaving it at rest, while the rear chisel can be operated alone. The pitman o connects treadle i with the bent or curved coupling-iron k, and the latter is fastened by its lower end to the chisel-rod b, in rear of the central block, D. The guide-rod P is also connected with the chisel-rod b, and extends through a central vertical hole in the upper portion of block D, and at its upper end it connects with retracting-spring S. It will now be understood that the chisels will be raised by the action of spring S, after being caused to descend by the action of treadle i. By means of the racks 3, pinions 6, and crank 5, the chisel-holders or guides, 4, may be adjusted, causing the space between the chisels to be varied to suit different kinds of work. The screw-bolt T will serve as a gauge, by which to limit the distance between the chisels Q Q¹ from time to time, as may be necessary, to form tenons of different thicknesses. The chisels are formed with an angular blade, for the purpose of forming the shoulder of the tenon; at the same time, making the side of it. The chisels may be made separate from the chisel-bars, and fastened to them by nuts and bolts, or in any suitable manner. The chisel represented in fig. 3 is formed of the parts Q² Q⁴, which are connected by a hinge-joint, r. The set-screw t is embraced by the arm d, as represented in the drawings, and enters the nut e, connected with the chisel-bar 7, and a link, f, is connected by pivots with both the chisel Q⁴ and the nut e formed at the bottom of the chisel-bar. By means of slots in the chisel-bar head, and screws in the chisel Q³ which pass through the slots, the chisel, or that part marked Q³, may be adjusted longitudinally, by means of set-screw t, which adjustment will cause the two parts to occupy the position indicated at y, in dotted lines, or they may be set at right angles. Chisels so formed and connected may be used to form tenons with shoulders standing at an angle to the tenon less than a right angle, which in certain kinds of work is very important. The bracket R and screw U serve to clamp and hold the lumber to be worked.

To cut a tenon on the end of a piece of lumber, it will be held by the set-screw U upon the table A, with the end upon which a tenon is to be made longitudinally placed between the chisels Q Q¹, when the movement of the treadle will cause the chisels to descend and cut away a portion of the wood, so as to form a tenon.

What I claim, and desire to secure by Letters Patent, is—

1. The adjustable chisel-bar guides 4, rack-bars 3, crank 5, and pinions 6, in combination with central block D and its plates 1 1, arranged and operating conjointly, as and for the purpose described.
2. The construction of the chisel, consisting of the blade Q⁴, attached to the blade Q³ by the hinge-joint r, and adjustable by means of screw t and link f, working in the arm e, whereby the chisel may cut a tenon at a right angle or less, all constructed and arranged to operate substantially as described.

In testimony whereof, I have hereunto set my hand, this 25th day of June, 1867.

WILLIAM F. COBB.
